ERNST HÄUSSLER, OF STUTTGART, GERMANY, ASSIGNOR TO UNION SPECIAL MASCHINENFABRIK, G. M. B. H., OF STUTTGART, GERMANY

OVEREDGING SEWING MACHINE

Application filed June 26, 1929, Serial No. 373,754, and in Germany July 11, 1928.

The invention relates to new and useful improvements in an overedging sewing machine for forming edge covering stitches in a fabric section.

5 An object of the invention is to provide an overedge stitching mechanism with a means which is adapted to engage the looper thread for drawing said thread taut so as to lay loops in the needle thread at the upper and lower faces of the fabric section which 10 extend to the edge of the fabric and are secured by the looper thread.

In the drawings:

15 Fig. 1 is a view in plan showing more or less diagrammatically the essential features of an overedge stitching mechanism with the improved take-up which engages the looper thread between successive stitches for drawing the same taut.

20 Fig. 2 is a view partly in section and partly in side elevation showing the feed bar, the feed dog, the means for operating the feed dog and the manner of supporting the looper thread take-up on the feed bar.

25 Fig. 3 is a perspective view showing the needle, the loopers, the stitch finger and the looper thread take-up; the presser foot is shown moved out of position to expose the parts beneath the same.

30 Fig. 4 is a diagrammatic view on an enlarged scale showing a fabric section having the overedging stitches applied thereto by my improved overedging mechanism.

Fig. 5 is a view partly in plan and partly 35 in section showing diagrammatically the needle, the thread carrying looper, the auxiliary looper, the feed dog and the looper thread take-up.

The invention is directed to an overedge 40 stitching mechanism which includes a needle, a thread carrying looper cooperating with the needle beneath the fabric and forming a loop which is passed through the needle thread loop. Also cooperating with the looper and needle is an auxiliary loop carrying 45 implement which engages the looper thread and forms a loop therein for the needle to enter on its next descent. This loop carrying implement is so mounted as to move in a 50 direction rearwardly as well as transversely

of the line of feed during the feeding of the fabric. Associated with these overedge stitch forming elements is a looper thread take-up which is mounted on the feed bar and moves with the feed bar. This looper thread take-up 55 engages the looper thread between successive stitches and draws on the thread so as to practically pull the looper thread straight. Inasmuch as the needle thread loop is passed through the looper thread loop, this will draw 60 the needle thread above the fabric to the edge of the fabric so that the needle thread between successive stitches is laid substantially into loop form.

Referring to Fig. 4 of the drawings, the 65 fabric being stitched is indicated at 31; the needle punctures at 30. The needle thread is indicated at *n*. This needle thread is formed into a loop which is passed through the fabric and the looper thread 7 is passed in loop 70 form through the needle thread loop. This needle thread loop is indicated at *n'* in Fig. 4. The movement of the loop into the needle thread loop draws this needle thread loop which is beneath the fabric well out to the 75 edge of the fabric. The looper thread which is formed into a loop is carried over the fabric so that the needle enters the loop on its next descent. The looper thread, as clearly shown in Fig. 4, is drawn taut and as a result 80 the loop is taken out of the looper thread and this will pull the needle thread which passed in loop form through the looper thread loop to the edge of the fabric, thus 85 forming a loop in the needle thread between successive stitches. This loop is indicated at *n''* in the drawings.

Referring more in detail to the mechanism for accomplishing this result, the machine is shown as provided with a needle 29 through 90 which a needle thread *n* is passed. It is also provided with a looper 1 which carries the looper thread 7. This thread carrying looper 1 is mounted on a looper carrier 2 which is attached to a collar 3 in turn mounted on 95 a shaft 4. The shaft 4 carries a sleeve which is fixed thereto and this sleeve is provided with an arm 6 attached to a link 5. The link 5 is given an endwise movement which im- 100 parts an oscillation to the looper 1. This

causes the looper 1 to move into and out of the needle thread loop.

Cooperating with this looper is a loop carrying implement 9. The loop carrying implement 9 is mounted on a carrier 10 fixed to the collar M which in turn is attached to the upwardly inclined shaft 12. The shaft 12 is provided with a sleeve carrying an arm 14 to which a link 13 is connected. As the link 13 is reciprocated, the loop carrying implement 9 will be oscillated and moved so as to engage the looper thread 7 and carry the looper thread in loop form over the fabric, positioning the same for the needle to enter on its next descent.

The loop carrying implement 9 is provided with a notch 15 which engages the looper thread and carries it over the fabric in loop form. The material is fed across the work support by a feed dog 22 mounted on a feed bar 21 which is connected to a feed rocker 20. The feed rocker 20 is provided with an arm 19, and an eccentric strap 18 connected to said arm cooperates with an eccentric 17 on the main shaft 16. The feed bar is raised and lowered by an eccentric 23 on the main shaft 16. Also mounted on the feed bar is a bracket 25. Said bracket is secured to the feed bar 21 by a screw 26 passing through a slot 27 in the bracket. This bracket is provided with the usual needle guard 28. This needle guard is so positioned that when the needle passes down through the fabric it will engage the rear face of the needle if it is deflected and insure that it is properly positioned so that the looper will pass in rear of the needle and not strike the same.

Also mounted on this bracket 25 is the improved looper thread take-up 24. Associated with the stitching mechanism is a stitch finger 33 carried by a combined supporting bracket and edge guide 32 which guides the edge of the fabric section 31 as it is directed to the stitching mechanism. As the stitches are formed they are formed about this stitch finger 33 and are then fed off from the end thereof.

From the above it is believed that the operation of the machine will be obvious; the needle passes through the fabric throwing out its usual loop which is entered by the thread carrying looper. The loop carrying implement engages the looper thread and forms a loop therein which is carried over the edge of the fabric and positioned for the needle to enter. As the needle is passing down into the fabric the feed dog is moving toward the front of the machine preparatory to engaging the fabric for feeding the fabric a stitch length when the needle is out of the fabric. On this forward movement of the feed bar the looper thread take-up engages the looper thread between the previously formed stitch and the concatenation of thread loops which have just been formed

and which are being drawn up as the needle descends. This pulls the looper thread taut taking out of the looper thread the loops which are formed therein. This straightening of the looper thread will pull the needle thread strands passing therethrough to the edge of the fabric section. This forms in the needle thread practically a loop located between successive needle punctures, which loop extends all the way to the edge of the fabric section. The looper thread is straight and is interwoven with the needle thread loop passing through the needle puncture and the loop in the needle thread between successive needle punctures.

While I have shown the take-up as mounted on the feed bar and movable therewith, it will be understood that this take-up may be otherwise formed and operated. The essential feature consists in the engagement of the looper thread so as to draw the same taut and thus produce needle thread loops on the upper and lower faces of the fabric section which are united at the edge of the fabric section. There is an advantage, however, in the mounting of the finger on the feed bar for the reason that when the length of the feed stroke is varied, the pull of the finger on the looper thread will likewise be varied so as to maintain its proper action on the looper thread.

Having fully described my invention, what I claim as new and desire to secure by Letters Patent, is:—

1. An overedging sewing machine including in combination a thread carrying needle, a thread carrying looper adapted to enter the needle thread loop, a loop carrying implement adapted to engage the looper thread and form a loop therein and position the same for the needle to enter, and means for engaging the looper thread between the looper and the previously formed stitch for drawing on said looper thread during the setting of the stitches so as to lay said looper thread substantially straight at the edge of the fabric section, thus forming loops in the needle thread on the upper and lower faces of the fabric which extend to the edge of the fabric section.

2. An overedging sewing machine including in combination a thread carrying needle, a thread carrying looper adapted to enter the needle thread loop, a loop carrying implement adapted to engage the looper thread and form a loop therein and position the same for the needle to enter, a four-motion feeding mechanism including a feed bar and feed dog for feeding the fabric, and means carried by the feed bar for engaging the looper thread when the feed bar is moved forward and for drawing on said looper thread during the setting of the stitches so as to lay said looper thread substantially straight at the edge of the fabric section, thus forming loops in the

needle thread on the upper and lower faces of the fabric which extend to the edge of the fabric section.

3. An overedging sewing machine including in combination a thread carrying needle, a thread carrying looper adapted to enter the needle thread loop, a loop carrying implement adapted to engage the looper thread and form a loop therein and position the same for the needle to enter, a feed bar, a feed dog carried thereby, a finger carried by said feed bar and adapted to engage the looper thread when the feed bar is moving forward and for drawing on said looper thread during the setting of the stitches so as to lay said looper thread substantially straight at the edge of the fabric section, thus forming loops in the needle thread on the upper and lower faces of the fabric which extend to the edge of the fabric section.

4. A sewing machine including in combination, a feeding mechanism, an overedging stitch forming mechanism including a needle and a thread carrying looper, and means for engaging the looper thread between the looper and the previously formed stitch for drawing on said looper thread during the setting of the stitches so as to lay said looper thread substantially straight at the edge of the fabric section being overedged.

5. A sewing machine including in combination, a feeding mechanism, an overedging stitch forming mechanism including a needle and a thread carrying looper, and means for engaging the looper thread between the looper and the previously formed stitch for drawing on said looper thread during the setting of the stitches so as to lay said looper thread substantially straight at the edge of the fabric section being overedged, said looper thread engaging means being actuated by said feeding mechanism.

6. In a sewing machine, the combination of a feeding mechanism, an overedging stitch forming mechanism including a needle and a thread carrying looper, said feeding mechanism including a feed bar, and a finger adjustably mounted on said feed bar and positioned so as to engage the looper thread between the looper and the previously formed stitch for drawing on said looper thread during the setting of the stitches, so as to lay said looper thread substantially straight at the edge of the fabric section.

55 In testimony whereof, I affix my signature.
ERNST HÄUSSLER.
